UNITED STATES PATENT OFFICE.

HENRY LEONARD HALL AND CECIL ALEXANDER SHARP, OF CRICKLEWOOD,
ENGLAND.

BUILDING AND FITMENT OF SAME FOR THE APPLICATION OF FINISHES TO SURFACES.

1,313,376.

Specification of Letters Patent.

Patented Aug. 19, 1919.

Application filed October 21, 1918. Serial No. 258,956.

To all whom it may concern:

Be it known that we, HENRY LEONARD HALL and CECIL ALEXANDER SHARP, both subjects of the King of Great Britain and

5 Ireland, residing at Langton Road, Cricklewood, in the county of Middlesex, England, have invented certain new and useful Improvements in Buildings and in Fitments of Same for the Application of Finishes to Surfaces, of which the following is a specification.

This invention relates to improvements in buildings and in fitments of same for applying finishes to surfaces which is particularly adapted for finishing off the surfaces of aeroplanes and other aircraft, which are covered with a fabric, and it has for its object the improvement of the conditions under which the persons applying the finishes work, rendering the application of the finishes less fatiguing and deleterious to the health of the operators, reducing the floor space required for the operation, and generally increasing the output and consequently reducing the cost.

We attain this end by arranging the parts to be treated so that the surfaces lie mainly in the vertical plane, by mounting said parts in horses or frames adapted to run in suitable guides, by arranging the drying chamber as a continuation of the applying or finished room so that the horses or frames can be progressively passed from one to the other as the work proceeds, by arranging a heating battery at the end of the applying or finishing room farthest from the drying chamber for heating said applying or finishing room, by arranging a second heating battery at the junction of the applying or finishing room and the drying chamber for super-heating said drying chamber, by providing means such as a fan or a blower for causing a current of air to pass by suction or pressure first over the heating battery at the end of the applying or finishing room then through said room into and through the drying chamber, by the provision of suitable main and by-pass flues for the air, and by the provision of 50 suitable louvered screens, shutters or the like for regulating both the volume and the velocity of the air passing into the apply-

ing or finishing room and for regulating the amount of air allowed to pass out of the applying or finishing room into the drying room.

In the accompanying drawing which shows by way of illustration a suitable and convenient building and plant in which the current of air is caused by suction:—

Figure 1 is a view in sectional elevation, and

Fig. 2 is a view in plan.

In both views similar parts are marked with like letters of reference.

At one end of the applying or finishing room *a* is a compartment *b* in which is located a heating battery *c* which may conveniently consist of a series of hot water pipes. In the wall between said compartment and the applying or finishing room are a series of openings *b*¹ which are fitted with shutters *d* for regulating the sizes of said openings.

At the other end of the applying or finishing room is the drying chamber *e* which is an extension of the said applying or finishing room. At the junction of the drying chamber with the applying or finishing room is a second heating battery *f* which may also consist of a series of hot water pipes. For convenience and economy the drying chamber may be divided into compartments as shown.

At the back end of the drying chamber is an exhaust flue or duct *m* which is in communication with the drying chamber by a series of openings *n* arranged at a suitable level. Above the drying chamber is a by-pass flue or duct *r* the front of which opens into the applying or finishing room and is provided with one or more adjustable shutters *s*. Both the main exhaust flue or duct *m* and the by-pass flue or duct *r* lead into a chamber *t* in which is a circulating fan *v* of the suction type.

The horses or frames *h* are supported and guided by suitable runners so that they are rigid to the pressure exerted in applying the finishes, and when the heating battery *c* is arranged on the floor as shown in Fig. 1 the bottom runners *h*¹ of the horses or frames are mounted on hinged arms *h*² so that they can rise and pass over said

heating battery as the horses or frames are advanced into the drying chamber.

The persons applying the dope stand—as shown in Fig. 1—close up to the entrance 5 to the drying chamber so that they can advance the work into said chamber as it proceeds. It will therefore be seen that by this method of carrying out the operation of applying the finishes there is no necessity 10 for the persons performing the operation to bend over their work thereby eliminating fatigue and consequently making for a greater output of work. The positions of the operators also make them practically 15 immune from inhaling the fumes given off by the finishes thereby materially improving the conditions under which they work, and the position of the work is such that both sides may be treated simultaneously.

20 What we claim as our invention and desire to secure by Letters Patent is:—

1. An improved building and fitments of same for the application of finishes to surfaces such as the parts of aeroplanes and the like, consisting of an applying or finishing room, a drying chamber contiguous to said room, a heating battery at the end of the applying or finishing room farthest removed from the drying chamber, a second heating 25 battery in the drying chamber, a series of horses or frames adapted to carry the work and to travel between the applying or finishing room and the drying chamber, and means for heating and circulating the air 30 through said room and chamber.

2. An improved building and fitments of same for the application of finishes to surfaces such as the parts of aeroplanes and the like, consisting of an applying or finishing room, a drying chamber forming an extension of said room, a heating battery at 40 the end of the applying or finishing room farthest removed from the drying chamber, a second heating battery in the drying chamber, a series of horses or frames adapted to carry the work and to travel between the applying or finishing room and the drying chamber, means for heating and circulating the air through said room and chamber, and 45 means for regulating the volume of said air and thereby regulating the temperature in said room and chamber.

3. An improved building and fitments of same for the application of finishes to surfaces such as the parts of aeroplanes and the like consisting of an applying or finishing room, a drying chamber forming an extension of said room, a compartment at the end of the applying or finishing 55 room farthest removed from the drying chamber at its junction with the applying or finishing room, a series of horses or frames adapted to carry the work and to travel between the applying or finishing room and the drying chamber, means for

heating and circulating the air through said room and chamber, and means for regulating the velocity and volume of said air, and thereby regulating the temperature of said room and chamber.

4. An improved building for the application of finishes to surfaces such as the parts of aeroplanes and the like, comprising an applying or finishing room, a drying chamber at one end of said applying or finishing 70 room, a compartment at the other end of the applying or finishing room in the dividing wall of which are a series of openings provided with louvers or shutters for controlling the areas of same, a heating battery in 75 said compartment, a second heating battery in the drying chamber, a series of horses or frames adapted to carry the work and to travel between the applying or finishing room and the drying chamber, a fan for 80 circulating the heated air through said compartment and chamber and means for regulating the temperature of the air in the drying chamber.

5. An improved building for the application of finishes to surfaces such as the parts of aeroplanes and the like, comprising an applying or finishing room, a drying chamber at one end of said room, a compartment at the other end of said room, in the dividing wall of which are a series of openings 90 provided with devices for controlling the areas of same, a heating battery in said compartment, a second heating battery in the drying chamber at the junction of said 95 chamber with the applying or finishing chamber, a plurality of horses or frames adapted to carry the work and to travel between the applying or finishing room and the drying chamber, a suction fan for drawing the air through said compartment, room and chamber, and means for regulating the velocity of said air and thereby regulating the temperature in the applying and finishing 100 room and in the drying chamber.

6. An improved building for the application of finishes to surface such as the parts of aeroplanes and the like comprising an applying or finishing room, a drying chamber at one end of said room, a compartment at 115 the other end of the said room, in the dividing wall of which are a series of openings provided with louvers or shutters for controlling the areas of said openings, a heating battery in said compartment, a second heating battery in the drying chamber at the junction of said chamber with the applying or finishing chamber, a plurality of horses or frames adapted to carry the work and to travel between the applying or 120 finishing room and the drying chamber, a suction fan for drawing the air through said compartment, room and chamber, means for by-passing some of the air past the drying chamber, and means for regulating the 125 130

velocity of the air and thereby regulating the temperature in the drying chamber.

7. A building for the application of finishes to surfaces such as the parts of aeroplanes and the like comprising an applying or finishing room *a*, a compartment *b* at one end of the applying or finishing room, and in communication with said room, a drying chamber *e* at the other end of said room, 10 openings *b*¹ in the wall between the compartment *b* and the room *a* a series of horses or frames *h* adapted to carry the work and to travel between the applying or finishing room and the drying chamber, a heating battery *c* in the compartment *b*, a second heating battery *f* in the drying chamber *e*, an exhaust flue or duct *m*, in communication with the drying chamber *e* and the exhaust flue or duct *m*, a suction fan *v* for drawing 15 on the exhaust flue or duct *m*, and shutters or the like *d* for regulating the amount of air passing from the heating compartment *b* into the applying or finishing room *a*.

8. A building for the application of finishes to surfaces such as the parts of aeroplanes and the like comprising an applying or finishing room *a*, a drying chamber *e* forming a continuation of the applying or finishing room, a compartment *b* at the end 20 of the applying or finishing room farthest removed from the drying chamber, and in communication with said room, a heating battery *c* in said compartment openings *b*¹ in the wall between the compartment *b* and 25 the room *a*, a second heating battery *f* in the drying chamber, a series of frames or horses *h* adapted to carry the work and to travel between the applying or finishing room and the drying chamber, an exhaust flue or duct 30 *m*, in communication with the drying chamber *e*, a suction fan *w* for drawing air into and through the exhaust flue or duct *m*, a

by-pass *r* in connection with the applying or finishing room *a*, shutters or the like *d* for regulating the amount of air passing 45 from the heating compartment *b* into the applying or finishing room *a*, and shutters or the like *s* for regulating the amount of air allowed to pass through the by-pass flue or duct *r*. 50

9. A building for the application of finishes to surfaces such as the parts of aeroplanes and the like, comprising an applying or finishing room *a*, a drying chamber *e* contiguous to said applying or finishing room, a compartment *b* at the end of the applying or finishing room farthest removed from the drying chamber, and in communication with said chamber, a heating battery *c* in said compartment, a second heating battery *f* at the junction of the drying chamber with the applying or finishing room, a plurality of frames or horses *h* adapted to carry the work and to travel between the applying or finishing room and 60 the drying chamber, an exhaust flue or duct *m*, in communication with the drying chamber, a chamber *t* in communication with the exhaust flue or duct, an exhausting fan in the chamber *t*, a by-pass flue or duct *r* connecting the applying or finishing room with the chamber *t*, shutters or the like *d* for regulating the volume of air allowed to pass from the heating compartment *b* into the applying or finishing room, and shutters or the like *s* for regulating the volume 65 of air allowed to pass out of the applying or finishing room through the by-pass flue or duct. 70

In witness whereof we have signed our 80 names.

HENRY LEONARD HALL.
CECIL ALEXANDER SHARP.
